UNITED STATES PATENT OFFICE.

JOHN FRANKLIN MacINDOE AND PETER THOMAS McGLYNN, OF PHILADELPHIA, PENNSYLVANIA.

REVERSIBLE ROTARY TURBINE-ENGINE.

No. 833,073.

Specification of Letters Patent.

Patented Oct. 9, 1906.

Application filed December 28, 1905. Serial No. 293,592,

To all whom it may concern:

Be it known that we, JOHN FRANKLIN MacINDOE and PETER THOMAS McGLYNN, citizens of the United States, residing at Philadelphia, in the county of Philadelphia and State of Pennsylvania, have invented a new and useful Improvement in Reversible Rotary Turbine-Engines, of which the following is a specification.

10 This invention relates to certain new and useful improvements in reversible rotary turbine-engines, and has for its object a construction in which ample provision is made for the escape of the expanded steam or other 15 propulsive medium after it has operated upon and exerted its fullest force upon the piston, so that it will not check or retard the piston, and thus enabling it to exert its highest speed and force with the least possible 20 propulsive medium.

The invention also contemplates certain other improvements and advantages which are attained by the peculiar construction, combination, and arrangement of parts, as 25 will be fully set forth in the following specification and pointed out in the claims, reference being had to the drawings, in which—

Figure 1 is a perspective view of our engine complete. Fig. 2 is an end view of the opposite side to that shown in Fig. 1. Fig. 3 is a sectional elevation drawn on the irregular lines 3 3 of Fig. 5, and Fig. 4 is a section drawn on the line 4 4 of Fig. 5. In this view one of the steam-boxes is shown in elevation. 35 Fig. 5 is a sectional view drawn on the line 5 5 of Fig. 3. Fig. 6 is a detail elevation of the piston. Fig. 7 is an enlarged detail sectional view drawn through a portion of the piston and illustrating the arrangement of the packing-strips. Fig. 8 is a detail perspective view of the packing-strips. Fig. 9 is a detail perspective view of one end of one of the reverse-valves. Fig. 10 is an enlarged detail section drawn on the line 10 10 of Fig. 3. In 40 this view the piston has been removed. Fig. 11 is an enlarged detail section drawn on the irregular line 11 11 of Fig. 4. Fig. 12 is a detail view of one of the steam-boxes. Fig. 13 and Fig. 13^a are detail views illustrating the 45 valve for controlling the port in the steam-box. Fig. 14 is a detail view, partly in section, of one end of the valve-cylinders. Fig. 14^a is a detail sectional view drawn through one of the valve-chambers and illustrating a

slight modification. Fig. 15 is a detail perspective view of one of the cranks for operating the valves, and Fig. 16 is a detail sectional view drawn on the line 16 16 of Fig. 10.

In constructing an engine in accordance with our invention we employ a casing A, comprising the heads or ends A' A' and a rim A², all being securely bolted to form a steam-tight compartment. One end of the rim is of a larger diameter than the opposite end, and fitting therein is a divisional plate C, which divides the casing into two compartments D and D', one of which, D, forms a live-steam chamber, and the other, D', together with a cylinder to be explained later, forms exhaust and piston chambers.

Positioned within the space D' is a double-rim cylinder E, which is tightly held between one head of the casing and the divisional plate, which thus divides the chamber D' into three compartments D², D³, and D⁴, the compartment D⁴ providing a piston-chamber and spaces D² and D³ annular exhaust-chambers which communicate with the piston-chambers through ports F and G, arranged in and extending through the rims on lines substantially tangential to the circumference of the rims. The ports F establish communication between the piston-chamber and the exhaust-chamber D³ and the ports G between the piston-chamber and the exhaust-chamber D². The latter ports extend through ribs H, cast integral with the rims of the cylinders, and do not communicate with the chamber D³.

Journaled in suitable hub-bearings in the heads of the casings and extending through the partition-plate C is a shaft I, having a piston J keyed thereon, which snugly fits within the chamber D⁴, and around its entire periphery the piston is formed with a plurality of alternating seats or rows of steam-pockets J' and J². The pockets J' in alternate rows are deepest at one end to provide a broad surface J³, against which the steam strikes to drive the piston in one direction, while the pockets J² of each alternate row are deepest at the opposite end, thus providing a broad surface J⁴ for the impact of steam to drive the piston in the opposite direction.

Arranged within the chamber D² of the casing at diametrically-opposite points are valve-cylinders K, and in order to provide for a free passage of the expanded steam

past the cylinders K and make the chamber D² continuous we extend or bulge the periphery of the casing, as shown at A³. Each valve-cylinder is provided upon opposite sides and in alternate position with exhaust-ports K' and K², to which are connected expanded nozzles K³ and K⁴, respectively, which extend as nearly tangentially through both rims of the cylinder as is practical, to 10 exhaust the live steam into the pockets of the piston. In each valve-cylinder is held a rotary valve L for controlling the steam-ports, and in order to provide a free passage for the steam throughout the entire length 15 of the cylinders we construct each valve of a shaft L', having arms or segmental disks L² and L³ radiating therefrom in alternate directions to cover the steam-ports K' and K², respectively. The shafts are also provided 20 with a series of arms L⁴, which engages the opposite sides of the cylinders to those in which the ports are arranged, and thereby providing a counterbalance for the shaft to hold it in perfect alinement and insure the 25 arms or disks being snugly fitted over the ports. It is of course understood the interior of the cylinders are ground perfectly smooth, especially at the points surrounding the discharge-ports, so as to provide seats 30 for the arms or disks, and if it should be found desirable the cylinders could be provided with raised seats for the arms or disks, as shown in Fig. 14^a of the drawings.

One end of each valve-shaft is extended 35 through a stuffing-box a in the head of the casing, and to their extreme ends are connected crank-arms M, to which are connected links M', whose opposite ends are connected to arms M² of a disk M³, that is revolubly 40 mounted upon the journal box or hub of the casing-head, and extending from the disk is a controlling-lever M⁴, carrying a ratchet-lever which works upon a rack-bar fastened to the casing. It is obvious that by throwing 45 the lever either set of ports in the cylinder may be simultaneously opened or closed, or both sets closed, as may be desired.

One end of each valve-cylinder extends through the divisional plate C and is connected 50 in any suitable way to a steam-box N, held in the live-steam chamber D², and each box has a port N', that is controlled by a slide-valve N², operating in guideways N³, upon the exterior of the boxes, and operated 55 by a crank-arm O, formed integral with or held upon the inner ends of rock-shafts O', journaled in the head of the casing adjacent the live-steam chamber, and in stuffing-boxes a' held to the casing-head. Upon the 60 outer ends of the shafts are held cranks O², to which is connected one end of links O³, whose opposite ends are connected to pitman-rods O⁴, extending from an eccentric-strap O⁵, that is held upon an eccentric-disk 65 O⁶, carried by the shaft I, and by which the

valves are intermittently operated to open and close the ports.

In the drawings we have shown the ports in the upper valve-boxes open and those in the lower boxes closed, which arrangement 70 provides for an alternate admission of steam into the boxes; but, if desired, we may by changing the position of the crank O² adjust the valves so that they will be successively opened and closed to provide admission of 75 steam to the piston at each quarter-revolution. By arranging the valves exteriorly upon the boxes the steam in the chamber holds them tightly against their seats.

The bodies of the valves are made substantially U or arch shape, with the ends of the parallel members terminating in flat plate-like disks either of which are of a size to completely cover the ports in the steam-boxes, and from the outer arch portion extend parallel-arranged arms between which operate the outer ends of the cranks O, and in order to decrease friction between the crank-arms and the arms of the valves we provide the cranks with sleeves which fit between the 90 parallel arms, as shown most clearly in Figs. 11 and 15.

Connected to the exhaust-chambers D² and D³ are pipes P and P', respectively, which connect with an exhaust-separator Q, 95 from which the exhausted steam finally escapes through a pipe R. The separator is divided into three compartments Q' Q² Q³, and the compartments Q² and Q³ communicate with the pipes P and P', respectively, 100 and the compartments with the compartment Q' through openings Q⁴, that are normally held closed by spring-pressed valves S. The purpose of this peculiar construction of separator provides against the back 105 pressure of the expanded steam and keeps either of the exhaust-chambers D² and D³ perfectly clear when the piston is operating in one direction or the other, and therefore completely controlling the expanded steam 110 and holding it from again entering the casing and coming into contact with the piston.

It will be readily understood that when the piston is working in one direction the steam will escape through one of the exhaust-pipes and thence into one of the compartments in the separator and pressing against the lower side of the valve will raise it and readily escape through the opening and finally out through the pipe R. The opposite valve in the meantime remains within its opening and prevents the admission of steam into the opposite compartment and back into the casing.

The operation of our invention is as follows: We will assume that the piston is being driven in the direction indicated by the arrow 1 shown in the upper half of Fig. 3 of the drawings. Steam is admitted through the pipe T into the live-steam chamber D, from 125

which it passes into the steam-boxes N, thence into the valve-cylinder and through the ports K', nozzle K³, and discharges into the pockets J' of the piston, which drives it in the direction indicated by the arrow, and after the piston has revolved a distance about equal to the length of one pocket the latter will be brought into register with the ports F, through which the steam escapes into the space D², and finally out through the pipe P into the separator. Of course it is understood that the valves have been previously set to open the ports K' and close the ports K³. Now should it be desired to operate or drive the piston in the opposite direction, or that indicated by the arrow 2 in Fig. 3 of the drawings, the valves are shifted so as to permit the escape of steam through the nozzles K⁴ into the pockets J², from which it escapes through the ports G into the compartment D² and finally out through the pipe P' to the separator.

In Fig. 3 of the drawings we have shown all of the valves set to open the ports K², which is the position they are held in when the piston is being driven in the direction indicated by the arrow 1; but in this view the section is arranged on an irregular line to illustrate one-half of the view as being drawn through one set of ports and pockets and the lower half through the adjacent set of ports and pockets, this being done for the purpose of economy of illustration.

The ribs or divisional walls formed by the pockets in the piston are provided with circumferential and lateral grooves, in which are held spring-actuated packing-strips J⁵, as shown most clearly in Figs. 6, 7, and 8 of the drawings.

From the foregoing it will be seen that we provide an exceedingly simple and highly efficient device for the purposes stated, and further comment is thought unnecessary.

Having thus described our invention, what we claim as new, and desire to secure by Letters Patent, is—

1. An engine of the kind described, comprising a casing having a live-steam chamber, a piston-chamber, and two independent exhaust-chambers, each of said exhaust-chambers communicating with the piston-chamber through independent sets of ports, a piston operating in the piston-chamber, nozzles for conducting live steam to the piston, and valves controlling the nozzles.

2. An engine of the kind described, comprising a casing having a live-steam chamber, a piston-chamber, and two independent exhaust-chambers, each of said exhaust-chambers communicating with the piston-chamber through independent sets of ports, a piston operating in the piston-chamber, nozzles for conducting live steam to the piston, valves controlling the inlets to the nozzles, exhaust-pipes connected with each ex-

haust-chamber, and a separator connected to said pipes.

3. An engine of the kind described, comprising a casing having a live-steam chamber, a piston-chamber, and two independent annular exhaust-chambers, each of said exhaust-chambers communicating with the piston-chamber through independent sets of ports, a piston rotatively mounted in the piston-chamber, and having pockets in its periphery, nozzles for conducting same into the said pockets, valves controlling the admission of steam to the nozzles.

4. An engine of the kind described, comprising a casing having a live-steam chamber, and two independent annular exhaust-chambers, each of the said exhaust-chambers communicating with the piston-chamber through independent sets of ports, a piston rotatively mounted in the piston-chamber, and having oppositely-disposed alternating rows of pockets in its periphery, independent sets of nozzles for conducting steam to the pockets, valves for controlling the inlets to the nozzles, independent exhaust-pipes connected to each exhaust-chamber, a separator connected to the said pipes, and means for controlling the admission of steam from the live-steam chamber to the said nozzles.

5. An engine of the kind described, comprising a casing having a live-steam chamber, two exhaust-chambers, and a piston-chamber, a piston rotatively mounted in the piston-chamber, and having a series of alternating rows of pockets in its periphery, valve-cylinders having discharge-nozzles communicating with the said pockets, valves controlling the admission of steam through the nozzles, an exhaust-pipe communicating with each exhaust-chamber, a separator connected to the pipes, means for controlling admission of steam to the nozzles and means for operating the valves.

6. An engine of the kind described, comprising a casing having a live-steam chamber, two annular exhaust-chambers, and a piston-chamber, a piston rotatively mounted in the piston-chamber and having a plurality of rows of pockets in its periphery, valve-cylinders having nozzles which communicate with the pockets of the piston, valves controlling the inlets to the nozzles, an exhaust-pipe connected to each exhaust-chamber, a separator connected to the said pipes, and means for providing an intermittent supply of steam to the nozzles.

7. An engine of the kind described, comprising a casing having a live-steam chamber, two annular exhaust-chambers, and a piston-chamber, said piston-chamber communicating with each exhaust-chamber through independent sets of ports, a piston rotatively mounted in the piston-chamber, and having a plurality of alternating pockets in its periphery, valve-cylinders having ex-

haust-ports in opposite sides thereof, nozzles connected to the ports, and extending into the piston-chamber for discharging steam into the pockets, valves for controlling the 5 ports and valves controlling the admission of steam to the valve-cylinders.

8. An engine of the kind described, comprising a casing having a live-steam chamber, two annular exhaust-chambers and a 10 piston-chamber, the said piston-chamber communicating with the exhaust-chambers through independent sets of ports, a piston rotatively mounted in the piston-chamber, said piston having a plurality of alternating 15 rows of pockets in its periphery, valve-cylinders having ports in the opposite sides thereof, which are arranged in alternating position, nozzles connected to the ports and extending into the piston-chamber for conducting steam to either set of pockets, valves controlling the said ports, means for operating the valves, and means for controlling the admission of steam to the valve-cylinders substantially as specified.

9. An engine of the kind described, comprising a casing having a divisional plate which divides the casing into two compartments, a cylinder held in one compartment and dividing the same into exhaust-chambers and a piston-chamber, a piston rotatively mounted in the piston-chamber, said piston having a plurality of rows of alternating pockets throughout its entire periphery, valve-cylinders having ports upon each side 35 thereof which are arranged in alternate position, nozzles connected to each port and communicating with the said pockets in the piston, valves for controlling the said ports, means for controlling the admission of steam 40 to the valve-cylinders, exhaust-pipes connected to the exhaust-chambers and a separator connected to the pipes, said cylinder within one of the compartments of the casing having sets of independent ports which establish communication between the piston-chamber and the exhaust-chamber.

10. The combination with a casing having two compartments, of a cylinder held in one compartment to provide a piston-chamber 50 and exhaust-steam chambers, the said cylinder having exhaust-ports which establish communication between the piston-chamber and the exhaust-chambers, a piston rotatively mounted in the piston-chamber, valve-cylinders having exhaust-ports arranged upon 55 opposite sides thereof and in alternate position throughout their length, nozzles connected to the ports and extending into the piston-chamber, valves controlling the said 60 ports, exhaust-pipes connected to the exhaust-chambers, a separator connected to the pipes, said separator having independent compartments with which the pipes communicate, and also a compartment which 65 communicates with each of the first-men-

tioned compartments through valve-controlled openings, and means for controlling the admission of steam to the valve-cylinders.

11. The combination with a casing having two compartments, of a double-rim cylinder 70 in one compartment providing two exhaust-chambers and a piston-chamber, the rims of the said cylinder having exhaust-ports which establish communication between the piston-chamber and each exhaust-chamber, a piston 75 rotatively mounted within the piston-chamber, and having rows of alternating pockets throughout its entire periphery, valve-cylinders held within one of the exhaust-chambers and having ports upon opposite sides 80 thereof which are arranged in alternating position, nozzles connected to each port and extending in diverging directions through the rims of the cylinders and opening into the piston-chamber to discharge steam into the 85 said pockets, rotary valves controlling the ports in the said cylinders, means for simultaneously operating the valves, steam-boxes arranged in the opposite compartment and connected to the valve-cylinders, said steam- 90 boxes having inlet-ports, valves controlling the ports, and means for operating the valves, and exhaust-pipes communicating with the exhaust-chambers.

12. The combination with a casing having 95 two compartments one of which provides a live-steam compartment of a double-rim cylinder held in one compartment providing the said compartment with a piston-chamber and two annular exhaust-chambers, the 100 rims of the said cylinder having independent sets of exhaust-ports which establish communication with the piston-chamber and the exhaust-chambers, a piston rotatively mounted in the piston-chamber, and having 105 rows of alternating pockets throughout its entire periphery, valve-cylinders held in one of the exhaust-chambers and having ports upon opposite sides which are arranged in alternating position throughout the length of 110 the cylinders, valves controlling the ports, steam-nozzles connected to the ports and extending in diverging directions to the said piston-chamber and communicating with the pockets in the piston, and a separator 115 having independent compartments which communicate with each exhaust-chamber and a compartment which communicates with each independent compartment through valve-controlled openings, and means arranged within the live-steam compartment 120 for controlling the admission of steam into the valve-cylinders.

13. The combination with a casing having two compartments, one of which provides a 125 live-steam compartment, of a double-rim cylinder arranged in one compartment dividing it into a piston-chamber and two exhaust-chambers, the said piston-chamber communicating with each exhaust-chamber through 130

independent sets of ports, valve-cylinders held in one exhaust-chamber and having exhaust-ports upon opposite sides thereof which are arranged in alternating position, nozzles connected to the ports and extending into the piston-chamber, valves controlling the said ports, a piston rotatively mounted in the piston-chamber, and having rows of alternating pockets throughout its periphery which are adapted to register with the nozzles and the said exhaust-ports in the double-rim cylinder, steam-boxes arranged in the live-steam compartment and connected to the valve-cylinders, said steam-boxes having inlet-ports, valves controlling the said ports, means for operating the valves to intermittently open and close the ports, and an exhaust-separator communicating with the exhaust-chambers.

14. The combination with a casing having two compartments one of which provides a live-steam compartment, of a double-rim cylinder held in one compartment dividing the same into a piston-chamber and two annular exhaust-chambers, each rim of the said cylinder having series of independent exhaust-ports which establish communication between the piston-chamber and the exhaust-chambers, a rotary piston mounted in the piston-chamber, said piston having a plurality of rows of pockets throughout its entire periphery, said rows being alternately arranged and adapted to register with the said exhaust-ports, independent sets of nozzles for conducting steam to the piston-pockets, valves for controlling the admission of steam through either set of nozzles, means arranged in the live-steam chamber for controlling admission of steam to the nozzles, and an exhaust-separator communicating with the exhaust-chambers, all substantially as specified.

15. The combination with a casing having a divisional plate therein which divides the casing into two compartments, of a double-rim cylinder held in one compartment and dividing it into a piston-chamber and two annular exhaust-chambers, the said exhaust-chambers communicating with the piston-chamber through independent sets of ports, a piston rotatively mounted in the piston-chamber, and having alternating rows of pockets throughout its periphery, valve-cylinders arranged in one of the exhaust-chambers and having exhaust-ports upon opposite sides, valves controlling the ports, nozzles extending from the ports in diverging directions and communicating with the piston-chamber to discharge steam into the pockets, steam-boxes held in the remaining compartment and connected to the ends of the valve-cylinders which project through the divisional plate, said boxes having inlet-ports, guides arranged upon the boxes, slide-valves operating in the guides to open and close the

ports, crank-arms journaled in the casing and operatively connected with the said slide-valves, means for operating the crank-arms as specified, and an exhaust-separator communicating with each exhaust-chamber. 70

16. The combination with a casing having a divisional plate which divides the casing into two compartments, of a double-rim cylinder fixedly held in one compartment dividing it into a piston-chamber and two annular exhaust-chambers, a piston having alternating rows of pockets throughout its entire periphery which are adapted for alinement with independent sets of exhaust-ports arranged in the rims of the cylinder and establishing communication between the piston-chamber and the exhaust-chambers, valve-cylinders held in one of the exhaust-chambers and extending at one end through the divisional plate, said cylinders having exhaust-ports upon opposite sides which are arranged in alternate position, expanded nozzles extending from each port in diverging directions and arranged to discharge into the pockets of the piston, valves controlling the admission of steam through the ports upon either side of the valve-cylinders, steam-boxes held in the remaining compartment of the casing and connected to the projected ends of the valve-cylinders, said boxes having inlet-ports, valves controlling the said inlet-ports, means for intermittently operating the valves to open and close the ports, and a separator having two independent compartments which communicate with each of the said exhaust-chambers and a compartment which communicates with each independent compartment, an exhaust-pipe communicating with the last-mentioned compartment, and valves controlling the communication between the independent compartments and the last-mentioned compartment. 90

17. An engine of the kind described comprising a casing having a live-steam chamber, a piston-chamber and two independent annular exhaust-chambers, each exhaust-chamber communicating with the piston-chamber through independent sets of ports, a piston operating in the piston-chamber, and means for conducting steam from the live-steam chamber to the piston. 110

18. An engine of the kind described comprising a casing having two independent annular exhaust-chambers, one arranged within the other, and a piston-chamber which communicates with each exhaust-chamber through independent ports, a piston operating within the piston-chamber, and nozzles extending through the exhaust-chambers for conducting live steam to the piston. 115

19. An engine of the kind described comprising a casing having a double-rimmed cylinder arranged therein and which divides the casing into two independent annular exhaust- 130

chambers, and a piston-chamber, the said rims having ports which communicate with each exhaust-chamber and the piston-chamber, a piston operating within the piston-chamber, and means for conducting steam to the piston.

20. An engine of the kind described comprising a casing having a double-rimmed cylinder arranged therein and which provides two annular independent exhaust-chambers and a piston-chamber, the said rims having independent ports which com-

municate with the piston-chamber, and each exhaust-chamber, a piston operating in the piston-chamber, nozzles for conducting live steam to the piston, and valves controlling the inlets to the nozzles, and exhaust-pipes communicating with each exhaust-chamber. 15
